UNITED STATES PATENT OFFICE.

FREDERICK W. RUTZKE, OF WELLSTON, MISSOURI.

WINDOW-SHADE FIXTURE.

1,149,294.

Specification of Letters Patent. Patented Aug. 10, 1915.

Application filed February 2, 1914. Serial No. 815,962.

To all whom it may concern:

Be it known that I, FREDERICK W. RUTZKE, a subject of the Emperor of Germany, and now residing in Wellston, county 5 of St. Louis, and State of Missouri, have invented a new and useful Improvement in Window-Shade Fixtures, of which the following is a specification.

My invention relates to window shade fixtures of the type in which the shade roller is mounted so that it may be bodily raised and lowered.

The principal objects of my invention are to provide a simple and efficient construction for facilitating the bodily adjustment of the roller of a window shade which is durable and reliable; and to attain certain advantages as will more fully appear hereinafter.

The invention consists in the parts, and the arrangements and combinations of parts as will be more fully set forth hereinafter.

In the accompanying drawings, which form part of the specification, and in which like reference characters refer to like parts throughout the different views, Figure 1 is a front elevation of a construction embodying my invention, showing it applied to a window of the ordinary form; Fig. 2 is a vertical section on the line 2—2 of Fig. 1; Fig. 3 is an enlarged side elevation of one end of a shade roller showing part of the invention applied thereto; Fig. 4 is a vertical section on the line 4—4 on Fig. 3; Fig. 5 is a vertical section on the line 5—5 on Fig. 6; Fig. 6 is an enlarged side view of the end of a shade roller opposite to the end shown in Fig. 3, the end of the roller being shown in section; Fig. 7 is a horizontal section on the line 7—7 on Fig. 5; Fig. 8 is a horizontal section on the line 8—8 on Fig. 5; Fig. 9 is a horizontal section on the line 9—9 on Fig. 5; Fig. 10 is a side elevation of the cord fastener; Fig. 11 is a vertical section on the line 11—11 on Fig. 10; Fig. 12 is a horizontal section on the line 12—12 on Fig. 10; Fig. 13 is a detail of a head on one of the brackets.

A device embodying the invention is capable of being attached to various forms of window frames and casings and of being used with various types of shade rollers; and, while there is shown in the drawings a common form of window frame and casing and shade roller, it is to be understood that

the application of the invention is not limited thereto.

A roller 1, upon which a shade 2 is wound, is provided at one end with a pin 3 (Fig. 6), embedded firmly in its end face in the center according to the usual construction. The pin 3 is enlarged at its exposed end to form a flange or rim 4. The other end of the roller 1 is provided with the usual pawl and ratchet spring controlling mechanism connected to an extending stud 5. The stud 5 is rectangular in cross-section and has a notch 6 in one of its edges.

Arranged on the sides of the window, preferably on the inside face of the window 70 casing upon the window stop 7, are guides 8 and 9. These guides 8 and 9 are the same, and a description of one will suffice for both. The guide 8 is made of a single strip of metal bent to form a base portion 75 10 which is secured to the face of the window stop 7 near the bottom and top thereof by screws 11. At one side margin of the base portion 10 is a lateral guide flange 12 extending at right angles to said base portion. At the other side margin of the base portion 10 the strip of metal is bent to form an outer guide flange 13 which is spaced from the base portion and has its marginal edge reinforced by a sharp rebend 14, 80 spaced from the lateral guide flange 12. The base portion 10, the lateral guide flange 12 and the outer guide flange 13 form a guide-way substantially L-shape in cross-section. The guides 8 and 9 extend from a point 90 about half way up the window to the top of the window.

In the guide 8 is mounted a bracket 15. The bracket 15 is substantially triangular in shape and extends parallel to the window 95 stop 7. The bracket 15 is formed of a single piece of sheet metal, and one side has an integral part bent at right angles to the body of the bracket and thence parallel to the bracket to form a substantially L-shape 100 flange 16 which fits into the L-shape guide-way of the guide 8. In the upper part of the bracket 15 is a round hole 17 at one side of the L-shape flange 16, and on the other side of said flange is a dished head 18 in 105 which is a slot 19 extending upwardly and having a rounded bottom. The slot 19 is arranged to receive the exposed end of the pin 3, the rim 4 of said pin engaging the concave side of the dished portion of the 110

head 18, as shown to the best advantage in Fig. 6.

In the other guide 9 is a bracket 20 having an L-shape flange 21 fitted into the L-shape guideway of the guide 9, in the same manner as the bracket 15. The bracket 20 has a dished head 22, near the center of which is a rectangular opening 23 corresponding to the size of the stud 5. 10 Leading from this rectangular opening 23 to the edge of the head 22 in a direction inclined to the vertical is a slot 24. A hook 25 is pivoted to the bracket 20 adjacent to the head 22 by an integral finger 26 passed 15 through a circular hole 27 in said bracket and bent back against the face of the head 20, as shown in Figs. 4 and 13. The hook 25 lies on the concave side of the dished head 22, and in its operative position, lies 20 over the end of the slot 24 and prevents the stud 5 from being lifted out of said slot. The bracket 20 is provided with a circular hole 28.

The brackets 15 and 20 hold the roller 1 in position so that it cannot be accidentally displaced from the brackets; but at the same time the roller 1 may be easily removed by a proper manipulation. To remove the roller 1, the hook 25 is swung back to leave 30 a free passage through the slot 24. The stud 5 is turned and lifted out of the slot 24. The bracket 15 is lowered until the roller 1 can be tilted so that the rim 4 on the pin 3 can follow the curvature of the 35 dished portion of the head 18. When the roller 1 is tilted in the proper manner, the pin 3 may be lifted out of the slot 19. The notch 6 in the stud 5 prevents the stud being pulled endwise from the bracket 20. 40 The rim 4 on the pin 3 likewise holds the pin from pulling endwise out of the bracket 15. A vertical movement of the stud 5 is prevented by the hook 25, and vertical movement of the pin 3 is prevented by the 45 engagement of the rim 4 with the dished portion of the head 18.

Knotted in the hole 28 in the bracket 20 is a cord 29, or other flexible member, which extends upward over a guide member 30 50 fastened to the head window stop 31, thence across the top of the window and over a second guide member 32, down the side of the window to a clip 33. Knotted in the hole 17 in the bracket 15 is another cord 34 55 which extends upward over the guide member 32 and thence down to the clip 33, which secures to it the end of the cord 29. The cord 34 extends down along the side of the window to any convenient point, where it 60 passes through a fastening device.

The device for fastening the cord 34 comprises a flanged cover plate 35 secured to the window stop 7 by a screw 36, and between this cover plate 35 and the face of 65 the window stop is disposed a wheel 37,

mounted for free rotation upon a screw 38. The wheel 37 is formed with a concave circular groove 39 near one end, and has a plurality of concave grooves 40 extending from the circular groove 39 diagonally to 70 the other end of the wheel. In the lower flange of the cover plate 35 is a pointed notch 41.

In the operation of the window shade fixture which I have shown and described, 75 the cord 34 is loosened by pulling upon its free end. The cord is thereby drawn out of the pointed notch 41, and the wheel 37 is partially rotated to bring the cord 34 into the circular groove 39. The shade roller 1 80 may now be bodily raised or lowered by a proper manipulation of the cord 34. As the cords 34 and 29, which are connected to the brackets 15 and 20 at the ends of the roller 1, are firmly secured together by the clip 85 33, it is certain that both ends of the roller 1 will be raised and lowered evenly. When the roller 1 has been adjusted to the desired position, the cord 34 is released. The weight of the roller 1 gives the wheel 37 part of a 90 revolution in a reverse direction, and one of the diagonal grooves 40 engages the cord 34 and guides it to the outside of the wheel 37, where it is clamped against the bottom flange of the flanged cover plate 35. The 95 pointed notch 41 forms an additional securing means for the cord 34.

Sometimes it happens that the width of the window varies slightly from the top to the bottom because of inaccuracies in the 100 construction or of the warping of the parts of the frame so that the brackets 15 and 20 are moved together or spread apart as they are raised and lowered. To prevent the brackets 15 and 20 binding in the guides 105 8 and 9 as they are pulled together or spread apart, a slight clearance is allowed between the L-shape flanges 16 and 21 of the brackets 15 and 20 and the L-shape guideways of the guides 8 and 9. The screws 11 act as stops 110 to limit the movement of the brackets 8 and 9 in their upper and lower positions. In the upper position, the roll of the shade upon the roller 1 is close to the under face of the top window stop 31 so as to prevent the 115 unwinding of the shade. The parts are made of sheet metal and may be easily and cheaply stamped and bent to the necessary shape.

Obviously, the construction I have shown and described is capable of considerable 120 modification without departing from my invention. Therefore, I do not wish to be limited to the exact construction which I have shown and described.

What I claim is:

1. A window shade fixture comprising guides fastened to a window frame along each side thereof, a bracket slidably mounted in each guide, one of said brackets having a dished head and a vertical slot extend-

ing to the edge of said head, the other of said brackets having a rectangular opening therein and a slot extending from one side of said rectangular opening diagonally relatively thereto to the edge of said bracket, a hook pivoted to said last mentioned bracket at a point substantially in line with said slot and arranged to swing across said slot near the end thereof adjacent to said opening, a shade roller having a pin fixed in one end thereof, said pin having an enlarged rim and being adapted to fit in the slot in the dished head of said first-mentioned bracket, the other end of said shade roller having a stud fixed therein, said stud being rectangular in cross-section and having a notch in one edge thereof, said stud being shaped to pass along the slot in said last mentioned bracket and into the rectangular opening therein, the notch in said stud being substantially as wide as the thickness of said last-mentioned bracket, and flexible members connected to said brackets for raising and lowering them in said guides.

2. In a window shade fixture, guides adapted to be fastened to a window frame near each side thereof, a bracket slidably mounted in each of said guides, one of said

brackets having a dished head with a slot therein extending from the outer edge to 30 the center of said head, the other of said brackets having a rectangular opening therein and formed with a slot extending from said rectangular opening to the edge of said bracket, a hook pivoted on said last-mentioned bracket and adapted to swing over the open end of said slot, said brackets being adapted to support the ends of a shade roller, said shade roller having a fixed pin at one end, said pin having an enlarged rim 40 and being adapted to fit into the slot in said dished head, the other end of said shade roller having a stud, said stud being rectangular in cross-section and provided with a notch in one of its edges, said stud being 45 adapted to be supported in said rectangular opening, and a flexible member connected to said brackets for raising and lowering said shade roller.

Signed at St. Louis, Mo., this 31st day of 50
January, 1914.

FREDERICK W. RUTZKE.
